WATER-GAGE.

1,072,608.

Specification of Letters Patent.

Patented Sept. 9, 1913.

Application filed April 9, 1913. Serial No. 760,069.

To all whom it may concern:

Be it known that I, GEORGE J. HATZ, a citizen of the United States, and a resident of the city of Omaha, county of Douglas, 5 and State of Nebraska, have invented certain new and useful Improvements in Water-Gages, of which I do declare the following to be a full, clear, and exact description, reference being had to the accompanying drawings, forming part of this 10 specification.

My present invention has relation to that class of water gages more especially adapted for determining the height of water 15 within steam boilers, and the object of the invention is to provide a simple, strong, light and effective construction of water gage and one in which all danger of leakage will be avoided.

20 An example of the type of water gage to which my invention relates is set forth in Letters Patent No. 1,051,105, granted to myself and Charles E. Fuller, as assignee, January 21, 1913.

25 The present invention consists of the features of novelty hereinafter described, illustrated in the accompanying drawings and particularly pointed out in the claims at the end of this specification.

30 Figure 1 is a front view of a water gage embodying my invention. Fig. 2 is a view partly in central vertical section on line 2—2 of Fig. 1 and partly in elevation. Fig. 3 is a view in cross section on line 3—3 of 35 Fig. 1. Fig. 4 is a view in front elevation showing my invention applied to a duplex water gage. Fig. 5 is a view in cross section on line 5—5 of Fig. 4.

The casing 1 of my improved water gage 40 is preferably a casting provided with a channel 2 for the column of water. As shown, the stop and bottom of the channel 2 are threaded to receive the coupling pipes 4 and 5. I have shown the back portion of the casing 1 as recessed and strengthened by a central, longitudinal rib 6 and transverse ribs 7, as by this means lightness and great strength are given to the casing. The casing 1 is formed with a chamber 10 adapted 45 to receive the sight glass 11. The inner portion of the chamber 10 is provided with a ledge or shoulder 12 between which and the sight glass 11 is interposed a gasket 13.

50 The sight glass 11 is shown of such dimension as to approximately fill the cham-

ber 10, and this sight glass is preferably of T-shape; that is to say, the sight glass is provided with an outwardly projecting portion 14 that extends centrally beyond the side portions 15 of the glass. This T-shaped construction of sight glass is attended with various advantages which will hereinafter more fully appear. The casing 1 is formed with an outwardly projecting wall 16 that surrounds the chamber 10 of the casing and is offset therefrom, and this wall 16 forms, with the projecting portion 14 of the sight glass, when the latter is in position, a stuffing box adapted to receive suitable packing 17. 70

In my improved construction, the cover 20 is connected to the casing 1 by suitable bolts 21 that enter threaded seats formed in the wall of the casing. The cover 20 is provided with a sight opening and with an inwardly projecting gland 22 adapted to enter the stuffing box or space between the projecting portion 14 of the sight glass and the surrounding wall 16 of the casing. 75

In assembling the parts, the sight glass 80 11 will be placed within the chamber 10 of the casing 1, with the gasket 13 interposed between the inner face of the sight glass and the shoulder 12 of the casing, after which the packing 17 will be placed within 85 the stuffing box formed between the surrounding wall 16 of the casing and the raised portion 14 of the sight glass, and this packing will extend across the abutting walls of the chamber 10 and sight glass 11. 90 The cover 20 will then be set in position and, by tightening the screws 21, the gland 22 of the cover will tightly compress the packing 17 within the stuffing box. By 95 tightening the screws 21, the pressure of the gland 22 will cause the soft packing material 17 to be forced laterally against the surrounding wall 16 and the edge of the projecting portion 14 of the sight glass 11. It will thus be seen that an exceedingly 100 tight joint is formed between the sight glass and the casing so that all danger of leakage around the edges of the sight glass is avoided. In fact, when the packing 17 is compressed, as above indicated, the escape of 105 the fluid from the casing is effectively guarded against at three points, viz: at the inner gasket 13 that is firmly compressed between the sight glass and the casing; again, by the packing extending across the 110

abutting walls of the chamber and of the sight glass, and, again, by the compression of the packing 17 against the surrounding wall 16 of the casing and the outwardly projecting portion 14 of the sight glass.

It will be observed that the outwardly projecting portion 14 of the sight glass is somewhat smaller than the sight opening of the cover 20, so that when the parts are in position for use, a space is left between the edge of the projecting portion of the sight glass and the gland 22 of the cover. This is a desirable feature, since, in case any slight leakage should occur, the water will not come in contact with the raised or outwardly projecting face of the sight glass, but all drippings will follow the inner edge of the gland and, hence, the danger of smearing the face of the sight glass is avoided.

The packing 17 is of such flexible or elastic material that, when it is compressed, it effectively fills every adjacent crevice and the gland 22 most effectively serves to prevent any danger of the packing blowing out, and, indeed, the greater the pressure upon the gage glass, the more firmly will the packing 17 be forced laterally against the surrounding wall 16 of the casing and against the edge of the projecting portion of the sight glass.

In order to enable the cover 20 to be readily removed without danger of breaking the sight glass, I provide the cover with one or more threaded openings 30 that are arranged opposite the wall of the casing 1, so that when it is desired to remove the cover it is only necessary to withdraw the bolts 21 and then, by inserting one of these bolts into the supplemental threaded openings 30, the cover 20 may be forced away from the casing. This is a desirable feature since, after the covers of sight glasses have been in use for some time, they are apt to stick and, if a hammer or like instrument is used in loosening the covers, there is danger of injuring the sight glass.

In Figs. 4 and 5 of the drawings, my invention is shown as applied to a duplex water gage—that is to say, a gage in which the height of a column of water may be observed from opposite sides of the gage. In this form of my invention, the casing 1^a has a central, inwardly projecting wall 1^b extending around the interior of the casing. As shown, the central space within the wall 1^b is connected by channels formed in the offset portions 41 and 42 with the couplings 4 and 5. In this form of the invention, two sight glasses 11 are used, each of these sight glasses being of T-shaped construction—that is to say, having an outwardly projecting portion 14, as before described. Between each of the sight glasses 11 and the interior wall 1^b of the casing is interposed a gasket 13 and, around each of the chambers 10 in

which the sight glasses 11 are contained, the casing is formed with a projecting wall 16 offset from the chamber 10. In this form of the invention, as in that hereinbefore described, each offset wall 16 forms, with the projecting portion 14 of the corresponding sight glass, a stuffing box in which is placed suitable soft or flexible packing 17 that is compressed by the gland 22 of the corresponding cover 20.

It will be understood that each of the covers 20 is held in place by screw bolts 21, as hereinbefore described, and each of the covers is provided with a supplemental threaded opening 30 to enable the covers to be readily removed, as hereinbefore set forth.

What has been said with respect to the advantages of my invention as applied to the sight glass shown upon Sheet 1 of the drawings, is applicable also to the duplex sight glass illustrated upon Sheet 2.

I wish it to be understood that the details of construction above set out may be varied without departing from the scope of the invention, and that features of the invention may be employed without its use as an entirety.

Having thus described my invention, what I claim as new, and desire to secure by Letters Patent, is:

1. A water gage comprising a casing having a chamber to receive a sight glass and having an outwardly projecting wall offset from and surrounding said chamber, a sight glass within said chamber having an outwardly projecting portion forming with said surrounding wall a stuffing box, a cover having a gland extending within said stuffing box and suitable packing within said stuffing box.

2. A water gage comprising a casing having a chamber to receive a sight glass and having an outwardly projecting wall offset from and surrounding said chamber, a sight glass within said chamber having an outwardly projecting portion forming with said surrounding wall a stuffing box, a cover having a gland extending within said stuffing box and suitable packing within said stuffing box, said gland and packing extending across the abutting walls of the chamber and sight glass.

3. A water gage comprising a casing having a sight glass chamber provided with a shoulder extending around the water space and having an outwardly projecting wall offset from and surrounding said chamber, a sight glass within said chamber having an outwardly projecting portion forming with said surrounding wall a stuffing box, a gasket arranged between the sight glass and said shoulder, a cover having a gland extending within said stuffing box and suitable packing within said stuffing box.

4. A water gage comprising a casing hav-

ing a chamber to receive a sight glass and having an outwardly projecting wall offset from and surrounding said chamber, a sight glass within said chamber having an outwardly projecting portion forming with said surrounding wall a stuffing box and having side walls at substantially right angles to the plane of said glass, the outer face of the side portions of said glasses being substantially parallel with the mouth of said chamber, a cover having a gland extending within said stuffing box and suitable packing within said stuffing box and extending across the abutting walls of the chamber and sight glass.

5. A water gage comprising a casing having a chamber to receive a sight glass and

having an outwardly projecting wall offset from and surrounding said chamber, a sight glass substantially filling said chamber and 20 having an outwardly projecting portion forming with said surrounding wall a stuffing box, a cover having an opening larger than the projecting portion of said sight glass so as to leave a space between said 25 projecting portion of the sight glass and the cover, said cover having a gland extending within said stuffing box and suitable packing within said stuffing box.
